United States Patent Office

Des. 213,551
Patented Mar. 18, 1969

213,551

SEAT CUSHION

Morris Cohen, 1/2 Levindale Hebrew Home and Infirmary, Belvedere and Greenspring Aves., Baltimore, Md. 21215

Filed Dec. 20, 1967, Ser. No. 9,866

Term of patent 14 years

U.S. Cl. D15—8
Int. Cl. D6—02

FIG. 1.

FIG. 2.

FIG. 3.

FIG. 4.

FIGURE 1 is a front perspective view of a seat cushion showing my design;

FIG. 2 is a view of the upper back of the seat cushion;

FIG. 3 is a side view of the seat cushion, and

FIG. 4 is a rear perspective view of the seat cushion in partially folded position.

I claim:

The ornamental design for a seat cushion, as shown.
